UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

1,369,480.

Specification of Letters Patent. Patented Feb. 22, 1921.

Application filed June 11, 1920. Serial No. 388,275.

To all whom it may concern:

Be it known that I, ISAAC SNOW, a citizen of the United States, and residing at Lawrence, in the county of Essex and State of 5 Massachusetts, have invented an Improvement in Feeler Mechanisms for Looms, of which the following description, in connection with the accompanying drawings, is a specification, like characters on the drawings representing like parts.

This invention relates to feeler mechanisms for looms, and has for one of its objects the provision of a feeler mechanism which shall be sensitive to the presence or 15 substantial absence of the filling on a detecting beat, and control the filling replenishing mechanism in accordance with the detected condition of the filling.

In that type of feeler mechanism wherein 20 the feeler is given a side swipe or movement longitudinally of the shuttle when the filling is substantially exhausted on a detecting beat, the feeler is either displaced laterally or given its side swipe movement by the front- 25 ward pressure against it, or by some means acting to displace the feeler on a detecting beat. In the present invention, however, the feeler is mounted upon a feeler carrier which is movable toward and from the front of 30 the loom, and a feeler actuator acts normally upon the feeler when it is in its rearward position to maintain it in feeling relation with the adjacent parts, and when the feeler is moved frontwardly by the front- 35 ward pressure on a detecting beat, to displace it laterally, or in a direction longitudinally of the shuttle, provided the filling is substantially exhausted. To give the feeler sufficient time to embed its toothed 40 engaging end into the filling, the feeler actuator acts progressively with increased energy, tending to displace the feeler laterally as it moves frontwardly, so that after the teeth of the feeler have embedded them- 45 selves, or itself, into the filling, the feeler actuator will not effect lateral movement or displacement of the feeler, provided a working supply is present, but will effect such movement when the filling is substantially 50 exhausted.

In the drawings:—

Figure 1 is a perspective view of the feeler side of a loom, showing more particularly the present invention and its association 55 with the coöoperating parts;

Fig. 2 is a detached detail view on an enlarged scale, showing the action of the feeler when a working supply is present in the shuttle on a detecting beat;

Fig. 3 is a view similar to that of Fig. 60 2, showing the action of the feeler mechanism when the filling is substantially exhausted on a detecting beat.

The loom frame 1 has secured thereto the brackets 2, one at each side of the loom, 65 in which is supported for rocking movement the transverse or rock shaft 3, which may be of usual construction. Rising from the rock shaft 3 is the arm 4, to which is connected at 5 the latch 6, the rear end portion of which is adapted to be engaged at times by an actuator 7 which may be conveniently formed as part of or connected to the cam follower, as usual in this general type of loom. In the present instance, the 75 latch 6 has a rear engaging portion 8 which is pivoted to the latch at 9, and is normally under balance, so that the rear end 8 is normally below the path of the operating member 7. Pivotedly connected to the 80 support 10 at 11 is a bell crank lever, one arm 12 of which underlies a finger 13 of the rear end portion 8 of the latch 6. The other arm 14 of the bell crank is connected to the feeler mechanism by a transmitter 85 15 which may be conveniently formed as a rod or other suitable device, the construction being such that the rear end portion 8 of the latch 6 will normally occupy a 90 position out of the path of movement of the operating member 7, and will be moved into the path of movement of the operating member when the feeler is given its side swipe movement, as will presently appear. 95

The lay 16 may be of usual construction and have the shuttle-box 17 into which is picked the shuttle 18 which carries the filling carrier or bobbin 19. The front wall of the shuttle-box is provided with an opening 20 and the adjacent wall of the shuttle 100 100 is provided with an opening 21, the construction being such that when the shuttle is properly boxed, the openings will register to permit the entrance therethrough of the feeler.

The feeler in the present invention, is mounted upon a feeler carrier which is movable toward and from the front of the loom. There are two principal forms of such carriers known in the art,—one a slide, and 110

the other a swinging arm. In the present illustration, the slide form of feeler carrier is shown.

The shipper stand 22 has extending therefrom the bracket 23 which is provided with a slot 24 to which is adjustably secured the feeler support 25 by means of a bolt or other form of securing means 26.

The feeler carrier is mounted for reciprocating movement toward and from the front of the loom upon a feeler stand 27, which may be adjustably secured to the bracket or support 25. In the present instance of the invention, the feeler stand 27 is formed with the turned end portions 28 which extend below the support 25 and to which they may be adjustably secured by any suitable means. The front end portion of the feeler stand is provided with a projection 29, and the rear end portion of the stand is similarly provided with a projection 30, the two projections serving as appropriate guiding means for the feeler carrier 31. In the present instance of the invention, the two projections 29 and 30 are each provided with an opening through which the feeler carrier 31 extends, and in which it is supported for reciprocating movement.

The feeler 32 is pivotally connected to the feeler carrier 31 at 33, the pivotal connection being located between the rear and front end portions of the feeler 32. The rear end portion of the feeler is provided with engaging teeth 34, of any suitable character.

As a convenient form of feeler carrier and pivotal support of the feeler with reference thereto, the feeler carrier 31 is shown as formed of an upper and lower portion which may be formed integral and bent at the front end portion 35. Between the upper and lower portions of the feeler carrier the feeler 32 is located, as indicated in Fig. 1. This construction is a convenient way of relating the parts, but of course, it may be changed.

Pivottally mounted at 36 on the feeler stand, is the feeler actuator, the rear arm 37 of which has a bearing portion 38 which bears upon the side of the feeler 32. The other arm 39 of the feeler actuator extends frontwardly, and is under the influence of yielding means tending to force the end 38 of the actuator against the edge of the feeler. In the present instance of the invention, the feeler carrier has pivotally connected to it at 40, the rod 41 which extends through a lug 42 carried by the frontwardly-extending arm 39 of the feeler actuator. A spring 43 is interposed between the shuttle 44 and the lug 42, the construction being such that the spring normally tends to force the end 38 of the feeler actuator against the side or edge of the feeler.

When the parts are in normal position

with the lay back, the end 38 of the feeler actuator rests or bears upon the side of the feeler 32 at one side of its pivotal connection with the feeler carrier, and when the feeler is moved frontwardly on a detecting beat, the end 38 of the feeler actuator bears upon the feeler at the other side of its pivotal connection with the feeler carrier. In the present instance of the invention, the end 38 of the feeler carrier bears against the side of the feeler frontward of its pivotal connection 33 with the feeler carrier when the parts are in rearward feeling position, and thereby tends to hold the feeler in its proper feeling position. To prevent displacement of the feeler from such position under the pressure of the end 38 of the actuator, a stop is provided which, in the present instance of the invention, consists of a lug 45 which extends from the feeler and engages a side of the feeler carrier under the pressure of the feeler actuator when the parts are in normal position, as indicated in Fig. 1. When, however, the feeler is pushed frontwardly on a detecting beat, the end 38 of the feeler actuator bears upon the feeler rearwardly of its pivotal connection 33 with the feeler carrier, and tends to move the feeler laterally, or give it a side swipe movement.

The transmitter 15 is connected to the feeler at 46 and is moved by the feeler when the latter responds to the pressure of the feeler actuator and moves laterally upon a detecting beat, with the filling substantially exhausted.

The feeler actuator has a finger 47 which may project between the upper and lower members of the feeler carrier 31 and act as a guide to steady the swinging movement of the feeler actuator under the gradually and progressively increased tension placed upon the spring 43 as the feeler moves frontwardly on a detecting beat.

The feeler carrier is provided with a stop 48 to limit its rearward movement and in the present instance, the stop 48 is arranged to contact with the front projection or lug 29 of the feeler stand when the feeler carrier is in its rearward position.

The construction hereinbefore described presents a good, practical form of the invention, although in some of the details the features may be changed without departing from the true scope thereof. When a working supply of filling is present in the shuttle on a detecting beat, the toothed end portion of the feeler 32 engages the filling and is moved frontwardly thereby. As the feeler moves frontwardly, the feeler actuator, which before acted frontwardly of the pivot connection between the feeler and feeler carrier, is caused to act rearwardly of the pivotal connection of the feeler with the feeler carrier, and tend to turn the feeler or give it its side

swipe movement. Owing to the presence of filling in the shuttle, however, the feeler resists the tendency to side swipe movement, and the parts remain in the position substantially indicated in Fig. 2, as the lay beats up. It will be noted that as the feeler carrier moves forwardly, the spring 43 is progressively increased in tension, thereby progressively increasing the pressure of the end 38 of the feeler actuator against the feeler. When filling is substantially absent on a detecting beat, the feeler will no longer be held by the filling from moving laterally or swinging upon its pivotal connection with the feeler carrier under the impulse of the feeler actuator as the lay beats up, and the parts will assume position substantially as indicated in Fig. 3, thereby moving the transmitter 15 and effecting replenishment 20 of filling.

What is claimed is:—

1. In a feeler mechanism for looms, the combination of a feeler carrier mounted for movement toward and from the front of the loom, a feeler pivotally mounted between its ends on the feeler carrier, a feeler actuator pivotally supported at a fixed point and having a part that bears upon the feeler at one side of its pivotal connection with the feeler carrier when the feeler is in its rearmost position and that bears upon the feeler at the other side of its pivotal connection with the feeler carrier as the feeler is moved forwardly on a detecting beat, and a spring which operates through the feeler actuator tending to turn the feeler laterally on a detecting beat and is held from effecting such movement by engagement of the feeler with the filling on a detecting beat 40 until substantial exhaustion thereof.

2. In a feeler mechanism for looms, the combination of a feeler carrier mounted for movement toward and from the front of the loom, a feeler pivotally mounted between its ends on the feeler carrier, a feeler actuator pivotally supported at a fixed point and having a part that bears upon the feeler at one side of its pivotal connection with the feeler carrier when the feeler is in its rearmost position and that bears upon the feeler at the other side of its pivotal connection with the feeler carrier as the feeler is moved forwardly on a detecting beat, and a spring between the feeler carrier and feeler actuator tensioned by frontward movement of the feeler carrier on a detecting beat to gradually increase the tendency of the feeler actuator to turn the feeler laterally.

3. In a feeler mechanism for looms, the combination of a feeler carrier, a feeler pivotally mounted between its ends on the feeler carrier, a feeler actuator comprising a lever having one end engaging the feeler alternately forward and rearward of the

pivotal connection between the feeler and feeler carrier as the feeler and feeler carrier move forwardly on a detecting beat, and a spring acting through the feeler actuator to turn the feeler laterally when the filling is substantially exhausted on a detecting beat.

4. In a feeler mechanism for looms, the combination of a feeler carrier movable toward and from the front of the loom, a feeler pivotally mounted between its ends on the feeler carrier, a feeler actuator mounted to bear upon the feeler at one side of its pivotal connection with the feeler carrier when the feeler is in its rearward feeling position and at the other side of its pivotal connection with the feeler carrier as the feeler is moved forwardly on a detecting beat, and means for effecting replenishment of filling when the feeler is moved laterally by the actuator on a detecting beat.

5. In a feeler mechanism for looms, the combination of a feeler carrier movable toward and from the front of the loom, a feeler pivotally mounted between its ends on the feeler carrier, a feeler actuator mounted to bear upon the feeler at one side of its pivotal connection with the feeler carrier when the feeler is in its rearward feeling position and at the other side of its pivotal connection with the feeler carrier as the feeler is moved forwardly on a detecting beat, a spring acting upon the feeler actuator to cause it to bear upon the feeler, and means for effecting replenishment of filling when the feeler is moved laterally by the actuator on a detecting beat.

6. A feeler mechanism for looms, comprising, in combination, a feeler carrier, a feeler pivotally connected between its ends to the feeler carrier, a feeler actuator pivotally mounted at a fixed point and having a part to bear upon the feeler alternately forward and rearward of the feeler's pivotal connection with the feeler carrier on a detecting beat, and a spring progressively tensioned by frontward movement of the feeler carrier and acting upon the feeler actuator to turn the feeler laterally when filling is substantially exhausted on a detecting beat.

7. In a feeler mechanism for looms, a feeler stand, a feeler carrier mounted for sliding movement on the stand, a feeler pivotally mounted on the feeler carrier, and a feeler actuator which bears upon the feeler in front of its pivot and then in rear of its pivot as the feeler moves forwardly on a detaching beat.

8. A feeler mechanism for looms, comprising, in combination, a feeler carrier, a feeler pivotally connected between its ends to the feeler carrier, a feeler actuator pivotally mounted at a fixed point and having a part to bear upon the feeler alternately

- frontward and rearward of the feeler's pivotal connection with the feeler carrier on a detecting beat, a spring progressively tensioned by frontward movement of the feeler carrier and acting upon the feeler actuator to turn the feeler laterally when filling is substantially exhausted on a detecting beat, and means connected to the feeler for effecting replenishment of filling.
- 10 9. A feeler mechanism for looms, comprising, in combination, a feeler carrier which is supported for movement toward and from the front of the loom, a feeler which is mounted on the feeler carrier for frontward and rearward movement therewith and also for movement in a direction longitudinally of the shuttle, and a feeler actuator which exerts a lateral force upon the feeler progressively nearer its rear end as the feeler is moved frontwardly on a detecting beat and effects lateral movement of the feeler relative to the feeler carrier when the filling is substantially exhausted.
- 15 10. A feeler mechanism for looms, comprising, in combination, a feeler carrier which is supported for movement toward and from the front of the loom, a feeler which is mounted on the feeler carrier for frontward and rearward movement therewith and also for movement in a direction longitudinally of the shuttle, and a feeler actuator that exerts a force upon one part of the feeler to restrain its movement longitudinally of the shuttle when the feeler is
- 20 30 35 40 45 50 55 60 65 70 75 80 85 90 95 100
- 30 with and also for movement in a direction longitudinally of the shuttle, and a feeler actuator that exerts a force upon another portion of the feeler tending to move the feeler longitudinally of the shuttle when the feeler is moved frontwardly on a detecting beat.
11. A feeler mechanism for looms, comprising, in combination, a feeler carrier

which is supported for movement toward and from the front of the loom, a feeler which is mounted on the feeler carrier for frontward and rearward movement therewith and also for movement in a direction longitudinally of the shuttle, and a feeler actuator that bears upon a front portion of the feeler when the feeler is in rearward position and shifts its bearing on the feeler to a rearward portion of the feeler tending to move the feeler longitudinally of the shuttle as the feeler is moved frontwardly on a detecting beat.

12. In a feeler mechanism for looms, the combination of a feeler which is supported for movement toward and from the front of the loom and for movement in a direction longitudinally of the shuttle, and a feeler actuator that bears upon the feeler with a tendency to restrain movement of the feeler longitudinally of the shuttle when the feeler is in rearmost position, and bears upon another portion of the feeler with a tendency to move the feeler longitudinally of the shuttle when the feeler is moved frontwardly from its rearmost position.

13. A feeler mechanism for looms, comprising, in combination, a feeler that is pivotally supported for movement longitudinally of the shuttle and is held from such longitudinal movement by engagement with the filling until substantial exhaustion thereof, and a feeler actuator which bears upon the feeler alternately frontward and rearward of its pivotal support during a detecting beat and exerts a lateral force upon the feeler.

In testimony whereof, I have signed my name to this specification.

ISAAC SNOW.
